UNITED STATES PATENT OFFICE.

HENRY WURTZ, OF NEWARK, NEW JERSEY, ASSIGNOR TO AMERICAN
CHEMICAL EDUCATION COMPANY, A CORPORATION.

APPARATUS FOR DISTILLING COALS AND OTHER HYDROCARBONACEOUS SUBSTANCES.

No. 821,323.

Specification of Letters Patent.

Patented May 22, 1906.

Application filed April 13, 1905. Serial No. 255,354.

To all whom it may concern:

Be it known that I, HENRY WURTZ, a citizen of the United States, residing at Newark, in the county of Essex and State of New Jersey, have invented certain new and useful Improvements in Apparatus for Distilling Coals and other Hydrocarbonaceous Substances; and I do hereby declare the following to be a full, clear, and exact description of the invention, such as will enable others skilled in the art to which it appertains to make and use the same.

This invention relates to an apparatus for carrying out in a practical manner the process of distilling solid hydrocarbonaceous materials—such, for example, as cannel, block, splint, and other coals, peats, shales, lignites, and other mineral and organic substances—set forth, described, and claimed in my application entitled "Process of distilling coals and like substances" and filed November 21, 1904, Serial No. 233,706.

The object of the invention is, first, to provide a suitable apparatus in which to operate the said process in a practical, effective, and expedient manner; second, to construct the apparatus so that there shall be a complete separation between the fire or fires for producing the deoxidized air or heating the incombustible gases and the coal or other substance undergoing distillation, so that combustion of the material will be prevented absolutely; third, to provide means for removing the residual coke when distillation of a charge is completed and recharging the apparatus quickly and easily; fourth, to provide means for regulating or controlling the temperature of the air or gases in the apparatus, and, fifth, to provide means for moving the currents of heated deoxidized air or gases through the apparatus rapidly and for drawing the vapors arising from the decomposition of the coal or other material from the apparatus and removing them from the heat before secondary action can take place, thereby arresting or preventing dissociation of the vapors or the formation of permanent gases.

The nature of the invention will be described in connection with the accompanying drawings, in which—

Figure 1 represents a vertical cross-section of the apparatus, taken through the center thereof. Fig. 2 is a horizontal section of the same, taken on line $x-x$ of Fig. 1. Fig. 3 is a

sectional side elevation, on a reduced scale, of 55 the apparatus. Fig. 4 is a longitudinal vertical section of the casing which forms the receptacle for the material.

The apparatus for the distillation of the hydrocarbonaceous substances consists of an 60 exterior structure in which are embraced the fire chamber or chambers, the heat flue or flues, fuel-magazines, a compartment between the fire-chambers and the heat-flues, and a trough below the said compartment 65 into which the vapors descend on their way to a pipe leading to an exhauster by which they are drawn out and driven to the condenser. The apparatus also comprises a casing that fits snugly into the compartment 70 and in which the material to be distilled is placed and which is adapted to be readily and quickly removed into or withdrawn from the said compartment.

The exterior structure is preferably built 75 of plate steel or iron, and, as shown in the drawings, at the sides thereof near the bottom there are fire-chambers 11 between the exterior walls 22 and the walls 33 of the compartment B. The bottoms of these walls are 80 formed with flanges 44 55, that rest upon and are bolted to the base-frame 6, the flanges 44 of the compartment-walls being turned outward or projecting into the fire-chamber, so that on their inside the walls of the compartment present perfectly plane surfaces unbroken by flanges or other projections. The fire-chambers are lined with fire-brick, as at 88, and provided with grate-bars. The rear walls 99 of the fire-chambers are formed 85 by plates joined and riveted to the side walls, so as to close completely the chambers at the rear, and at the front they are closed airtight by flanged plates 1010, let into the front of the fire-chambers and secured by 90 bolts passed laterally through the flanges and the walls of the chamber. Below the fire-chamber are ash-pits 1111, and between the ash-pits and directly under the compartment B there is a trough E, having a vapor-exit 1210 at the rear and fitted with a flange 13, to which is fastened an exhaust-pipe 14, that leads into the casing of a rotary exhaust-fan E. (Shown in Fig. 3, but omitted from Fig. 1.) The walls of the ash-pit and of the 105 trough are formed by steel or iron plates flanged and riveted or bolted to the base-frame 6.

Above the fire-chambers are fuel-magazines H H. These are formed by plates 15 16, (the latter flanged at the bottom,) that rest on the frames 17 17, laid on the flanges of the exterior walls of the fire-chamber, the flanges of the walls 16 16, the exterior edges of the frames 17 17, and the flanges of the walls 2 2 being bolted or riveted together. The inner sides of the frames 17 17 are flanged, as at 18 18, and the bottoms of the inner walls 15 of the magazine are bolted or riveted to these flanges. At the top the magazines are fitted with exterior water-trough 19 19 to receive the rims of the covers 20 20, thus forming water seals for the said covers.

Between the walls 3 3 of the compartment B and the walls 15 15 of the fuel-magazines there are vertical heat-flues L L, leading from the fire-chambers.

The compartment is closed at the top by a cover 21, flanged and riveted to the walls of the magazines. The walls 3 3 of this compartment extend up to and connect with the cover 21, and a short distance from the cover they are provided with perforations 22 22 and bottom plates 24 24, which are provided with valve-seats 25 25 in valve-chambers M M. Valves 26 26 in said chambers have their rods passed up through rod-guides and through the perforations in the perforated tops of said rod-guides, so that the valves can be opened and closed either by hand or by mechanical means. Just under the cover 21 in the back walls of the heat-flues there are draft-openings 27 27, from each of which pipes lead to the stack. (Not shown.)

Longitudinally of the cover of the casing there is a vertical slot 28 between upward extensions 29 29 of the cover, which is open at the front. The tops of the extensions are turned over at right angles to form flanges on which a plate 30 is placed, luted with clay, and fastened to form an air-tight cover for the groove when distilling is going on.

31 31 are hooks the stems of which are passed down through the slot 28 into the compartment B, while the tops of the stems are provided with rings 31^a. The plate 30 serves as a cover for the slot 28, and the function of the hooks is to lift and carry the casing when it is moved in and out of the compartment.

The casing C is constructed of plate iron, steel, or any other suitable material, and consists of side and rear end walls riveted at the bottom to an angle-iron frame 33. The front, top, and bottom are open; but the side walls at or near the top are connected by two or more transverse rods 34 34, each of which at the center is bent upward to form a quirk 35 at the point where the hooks 31 take hold when the casing is to be moved in or out of the compartment, the quirk compelling the hooks to take and retain a middle position,

so that the casing will be held perfectly level when moved. The casing fits into the compartment easily, only space enough being left between to allow for expansion, so that as much as possible of the heat from the flues 70 will radiate through the walls and reach the contents of the casing. The casing is provided with longitudinal brackets 36, fixed to the sides, and on these brackets trays 37 are placed, but need not be fastened, so that they 75 can be slid in and out of the casing at the front or open end. These trays are not as long as the casing, and when filled with the material to be distilled they are staggered, so that spaces will be left between their alternate ends and the end walls of the casing. Thus the rear end of the topmost tray (see Fig. 3) is closed against the rear wall of the casing, a space 38 being left between its 80 front end and the door 39, that closes the front end of the casing; but the tray immediately beneath it is oppositely arranged, the space occurring between its rear end and the rear wall of the casing. These spaces thus occur at opposite ends of the casing alternately, a zigzag passage being thus formed through the casing. The heated products of combustion drawn through the casing are thus compelled to traverse the entire length of the trays and their contents twice, first 85 over the top and then under the bottom.

The front of the casing when distillation is going on is closed by a flanged plate 39, which is inserted in the open front with the flanges against the side walls, where they are secured by bolts, which are passed through the bearings and inserted in the open ends of the inclined slots in the edges of the side walls. The front of the compartment B and the front end of the slot 28 between the extensions 29 29, which is also open, are to be closed by means of a door V, which fits closely against the flanges 40 40 on the front ends of the walls of the compartment and the front ends of the extensions 29 29, and the joints 100 105 110 are made air-tight and gas-tight by luting them with clay and the door fastened by means of screw-clamps 40^a.

Above the apparatus and in vertical alignment with the slot 28 there is a trolley-rail 115 42, on which a trolley 43 runs. A pulley 44 is suspended from the trolley by a chain 44^a, which carries a hook 45, that engages a wire rope 46, fastened to the rings 31^a 31^a on the outer ends of the stems of the hooks 31 31. 120 These hooks 31 31 engage the quirks 35 35 of the rods 34 34, and the casing is thus suspended from the hook 45 of the pulley, as described.

The operation of the apparatus in the distillation of the coals, &c., is as follows: The casing rests when in the compartment on the base-frame 6, as shown by Figs. 1 and 3. To move it out of the compartment for the purpose of putting the material on the trays, it 125

is lifted, by means of the pulley, until it is suspended just above the base-frame 6, and (the door V of the compartment having been previously removed) the casing is run out of the compartment by means of the trolley. The trays are then filled with lumps of, say, cannel-coal, which may be heaped up more or less. The trays are then carefully adjusted, so that space will be left at alternate ends of adjoining trays, and thus a zigzag passage formed through the casing. The door 39 of the casing is then put in place to close the front end, and the casing is then run back into the compartment and lowered until it rests on the base-frame 6. The fires are then started up and the dampers 41 in the pipes 27, (only one of these pipes and dampers being shown,) leading to the stack, (not shown,) opened for a short time to quicken the fire.

When the temperature in the apparatus reaches, say, 750° Fahrenheit, or below red heat or incandescence, as indicated by the pyrometer P, the dampers are closed and the exhauster is started and driven at a high speed. The effect of this is to draw the hot, gaseous, neutral, or deoxygenized products of combustion up through the heat-flues, then through the perforations 22 22 into the valve-chambers, then downward into the casing, past the valves 26 26, through the zigzag passage, through the casing C, as indicated by the arrows. In passing downward following the said passage it necessarily passes over the top of the coal on the trays to the spaces between them and the end walls of the casing, and descending through these spaces it passes in the opposite direction under the bottoms of the trays. Thus the coal in each tray is exposed to the rapidly-moving currents of the hot products of combustion, and the action of the heat in drawing out the oils is continuous and rapid. The temperature not being sufficiently high to dissociate the initial products, tar, naphthalene, benzol, &c., are not developed, large quantities of paraffin are produced, and the residual coke is hard, porous, free burning, and practically quite devoid of volatile matter, these qualities assimilating it more nearly to charcoal than to the coke produced by high temperatures in coke-ovens. The temperature of the products of combustion is regulated by the valves 26, by means of which it can be maintained between 700° and 800° Fahrenheit, or below red heat or incandescence, at which point the desired results are obtained. By means of these valves the currents of heated gases or vapors are managed in such ways as to accomplish all the chemical objects aimed at. The currents of the products of combustion containing carbonic acid are made to pass through the decomposing coal from above downward, thus sweeping the heavy vapors away from the heat as rapidly as possible and preventing second-

ary action and dissociation. Hence the total absence of tar, naphthalene, and benzol and the unprecedented amount of phenols that are formed. Hence also the short duration of the operation compared to that of the white-hot gas-retort, in which the heat is largely expended in the work of dissociation of the first products.

I claim—

1. In an apparatus for distilling coals and other hydrocarbonaceous substances, spaced and staggered trays, for holding the substance to be distilled, inclosed in a compartment which is in communication on the one hand with a heat-flue from a fire-chamber adjoining the compartment, and on the other hand with an exhaust-pipe, and means for inducing currents of heated products of combustion to enter the compartment from the heat-flue and to zigzag over the substance on the trays, and under and around the ends of the trays and to draw the products of combustion and distillation out of the compartment and into the exhaust-pipe, substantially as specified. 75

2. In an apparatus for distilling coals and other hydrocarbonaceous substances, spaced and staggered trays, for holding the substance to be distilled, inclosed in a compartment which is in communication on the one hand with heat-flues from fire-chambers adjoining the two sides of the compartment, and on the other hand with an exhaust-pipe, and means for inducing currents of heated products of combustion to enter the compartment from the heat-flues and zigzag over the substance on the trays, and under and around the ends of the trays and to draw the products of combustion and distillation out of the compartment and into the exhaust-pipe, substantially as specified. 95

3. In an apparatus for distilling coals and other hydrocarbonaceous substances, spaced and staggered trays, for holding the substance to be distilled, inclosed in a compartment which is in communication on the one hand with heat-flues from fire-chambers adjoining the two sides of the compartment, and on the other hand with an exhaust-pipe, means for inducing currents of heated products of combustion to enter the compartment from the heat-flues and zigzag over the substance on the trays and under and around the ends of the trays, and to draw the products of combustion and distillation out of the compartment and into the exhaust-pipe, and means for controlling the inflow of the products of combustion to the compartment, substantially as specified. 110

4. In an apparatus for distilling coals and other hydrocarbonaceous substances, the combination of a fire-chamber and a compartment adjacent thereto, but separated therefrom by a wall, and a heat-flue leading from the fire-chamber, openings in the wall 125 130

between the heat-flue and a compartment for the passage of the products of combustion into the compartment, trays supported one above the other in the compartment and 5 staggered to form a zigzag passage through the compartment, an exhaust-pipe and an exhaust connected therewith to induce currents of products of combustion from the heat-flues into and through the compartment 10 and to draw the products of combustion and distillation out of the compartment and into the exhaust-pipe, substantially as specified.

5. In an apparatus for distilling coals and other hydrocarbonaceous substances, the 15 combination of fire-chambers and a compartment located between the same, heat-flues leading from the fire-chambers, openings leading to the heat-flues in the walls of the compartment, trays supported one above the 20 other in the compartment and staggered to form a zigzag passage through the compartment, an exhaust-pipe and an exhaust connected therewith to induce the products of combustion from the heat-flues into and 25 through the compartment and to draw the products of combustion and distillation out of the compartment and into the exhaust-pipe, substantially as specified.

6. In an apparatus for distilling coals and 30 other hydrocarbonaceous substances; the combination of one or more fire-chambers, a compartment adjacent to the fire chamber or chambers, heat flue or flues leading from the fire chamber or chambers to the compartment, and a casing inserted in the compartment having trays arranged in the same for 35 the coal, substantially as specified.

7. The combination of one or more fire-chambers, a compartment adjacent thereto, 40 a heat flue or flues leading from the fire chamber or chambers to the compartment, a casing open at top and bottom and having trays arranged therein to form a zigzag passage through the casing, and adapted to receive 45 the coal to be distilled, substantially as specified.

8. The combination of one or more fire-chambers, a fuel-magazine located above the fire-chambers having water-sealed tops, a compartment adjacent to the fire chamber or 50 chambers but divided therefrom by a partition or partitions, heat flue or flues leading from the fire chamber or chambers to the compartment and a casing located in the compartment having trays arranged therein 55 for the coal, substantially as specified.

9. The combination of one or more fire-chambers, a compartment adjacent thereto divided therefrom by a partition or partitions 60 through which openings lead into the compartment, a valve chamber or chambers located in the compartment and valves for controlling the temperature in the compartment, substantially as specified.

10. The combination of one or more fire-chambers, a compartment adjacent thereto, heat flue or flues leading to the compartment, a casing arranged in the compartment and having trays arranged therein to receive the coal said casing adapted to be moved into the 70 compartment during distillation and to be moved out of the same to discharge the residual coke and recharge with coal, all substantially as specified.

11. The combination of one or more fire-chambers, a compartment adjacent thereto, heat flue or flues leading to the compartment, valves for regulating the temperature in the compartment, a casing in the compartment having trays arranged therein for the coal, a 80 trough under the casing to draw the products of combustion and the vapors arising from the distillation of the coal out of the casing, all substantially as specified.

In testimony that I claim the invention 85 above set forth I have affixed my signature in presence of two witnesses.

HENRY WURTZ.
